(Cl. D58—26)

To all whom it may concern:

Be it known that we, Jack W. Soffer and George S. Hunt, both citizens of the United States, residing at the city of St. Louis, State of Missouri, and at the city of Pacific Palisades, county of Los Angeles, State of California, respectively, have invented a new, original, and ornamental Design for a Closure Cap for Steel Cans or Similar Articles, of which the following is a specification, reference being made to the accompanying drawing, forming a part thereof, in which:

Figure 1 is a perspective view of a closure cap for steel cans or similar articles, embodying our new design;

Figure 2 is a top plan view thereof;

Figure 3 is a bottom view thereof; and

Figure 4 is a side elevational view.

We claim:

The ornamental design for a closure cap for steel cans or similar articles, substantially as shown.

JACK W. SOFFER.
GEORGE S. HUNT.
